UNITED STATES PATENT OFFICE

116,752

DESIGN FOR A COMBINED MERCHANTISE DISPLAY CASE AND MIRROR

José Trojan, Chicago, Ill., assignor to Owen Householder and David C. Cohen, copartners, doing business as Crystal Manufacturing Co., Chicago, Ill.

Application July 20, 1939, Serial No. 86,101

Term of patent 3½ years

To all whom it may concern:

Be it known that I, José Trojan, a citizen of the United States, residing at Chicago, in the county of Cook and State of Illinois, have invented a new, original, and ornamental Design for a Combined Merchandise Display Case and Mirror, of which the following is a specification, reference being had to the accompanying drawing, forming part thereof.

I claim:

The ornamental design for a combined merchandise display case and mirror, substantially as shown.

JOSÉ TROJAN.
